UNITED STATES PATENT OFFICE.

GEORGE T. WILLIAMS, OF DENVER, COLORADO.

SPACE-BAND FOR LINOTYPE-MACHINES.

1,115,358.

Specification of Letters Patent. Patented Oct. 27, 1914.

Application filed August 22, 1913. Serial No. 786,163.

To all whom it may concern:

Be it known that I, GEORGE T. WILLIAMS, a citizen of the United States, residing in the city and county of Denver and State of Colorado, have invented certain new and useful Improvements in Space-Bands for Linotype-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in space bands or devices placed between the words in linotype composition to space the words evenly, and while my improved construction is more especially intended for use in connection with matrix bars, each carrying a complete set of characters employed in printing, my novel construction may be employed separately, and operated in the same manner as the space bands heretofore in use, in the Mergenthaler type of machine, for instance.

The object of my improvement is to increase the spacing range between the words in this class of machines, and to this end, I mount two movable spacing members upon the body of the band which is of uniform thickness throughout its length, one of the movable members being wedge-shaped and the other of uniform thickness. On the side of the body part where the movable wedge-shaped member is located and above the same, is arranged a stationary wedge-shaped part which is oppositely disposed with reference to the movable member, whereby when the movable wedge-shaped part is properly adjusted, it is caused to overlap the oppositely disposed stationary part, whereby the words are evenly spaced, the two wedge-shaped parts taken together constituting a device having parallel opposite sides. By virtue of this arrangement, the spacing of the words may be accurately varied to any extent desired.

The movable members of the space band have a dove-tailed connection with the body of the band, the movable parts carrying longitudinally arranged tongues of dove-tailed shape which engage grooves of counterpart shape formed in the structure when the parts are assembled, the tongues of one of

the movable members being spaced to constitute a groove of counterpart shape for the tongue of the other movable member. Hence, it becomes necessary that the tongues of these movable members shall extend beyond the members themselves in order that they may be accurately guided in the grooves which are in part formed by the tongue or tongues of another member when the latter is not correspondingly adjusted.

When this space band construction is employed in connection with a matrix bar carrying a complete set of characters as heretofore explained, it constitutes a continuation of the lower part of the bar, the portion of the bar carrying the matrix characters being arranged above, thus leaving the space band mechanism free for adjustment as it is located below the casting space or the space where the mold is located during the type casting operation. When, however, the construction is employed to form a space band separate from the matrix bar and adapted to be assembled in the manner similar to the ordinary space band, my improved construction is correspondingly arranged.

Having briefly outlined my improved construction, I will proceed to describe the same in detail, reference being made to the accompanying drawing, in which is illustrated an embodiment thereof.

In this drawing—Figure 1 is a side elevation of a matrix bar equipped with my improved space band construction. Fig. 2 is a similar view of the space band portion of the device illustrated in Fig. 1, but shown on a larger scale. The part illustrated in this view is the same as that located between the lines A and B in Fig. 1. Fig. 3 is a side view of the construction shown in Fig. 2, being a view looking in the direction of arrow 3, Fig. 2. Fig. 4 is a view similar to Fig. 3, but showing one of the movable space band members in a different relative position. Fig. 5 is a similar view showing the two space band members adjusted to perform their maximum word spacing function. Fig. 6 is a side elevation illustrating my improved space band construction shown as a device separate from the matrix bar. Fig. 7 is a cross section taken on the line 7—7, Fig. 5. Fig. 8 is a detail view of the body of the space band shown on the same scale as in Fig. 2, the stationary wedge being shown in place. Fig. 9 is a detail view

of the movable wedge-shaped member of the space band shown in side elevation. Fig. 10 is a similar view of the other movable member of the space band construction. 5 Figs. 11, 12 and 13 are sections taken on the lines 11—11, 12—12 and 13—13 of Figs. 8, 9 and 10, respectively. Fig. 14 is a section taken on the line 14—14, Fig. 8, viewed in the direction of the arrow. Fig. 15 is a 10 section taken on the line 15—15, Fig. 5, viewed in the direction of the arrow.

The same reference characters indicate the same parts in all the views.

Let the numeral 5 designate a matrix bar 15 of the general construction disclosed in my simultaneously pending application, Serial No. 768,968, filed April 28, 1913, for improvements in type setting and casting machines.

20 This device consists of a rigid member 6 having parts 7 and 8 arranged at its extremities and extending at right angles to the body part; these end portions being equipped with top and bottom extensions 9 and 10, respectively, to facilitate the use of the bar with a machine of suitable construction. But as this application is limited to the space band feature, no detail or explanation need be given, with reference to the 25 machine or mechanical construction with which it may be employed.

Connected with the outer extremities of the parts 7 and 8, is the part 12 of the matrix bar carrying or equipped with the 30 members 13 in which the matrix characters are formed. Below the lowermost matrix member 13, is located the space band part of the device which in its entirety may be designated by the numeral 14. The body 15 35 of this structure is provided with a relatively wide slot or longitudinally disposed opening 16 having at its opposite sides beveled walls 17. Slidably arranged on one side of this body member 14 is a wedge-shaped member 18 having two tongues 19 of dove-tail shape and separated to form a centrally located space 20 of dove-tailed shape. The tongues 19 extend longitudinally beyond the spacing portion of the 40 member as best illustrated in Fig. 9. When the parts are assembled, the outer beveled walls 21 of the tongues 19 engage the correspondingly inclined or beveled walls 17 of the body part 15 of the space band construction.

On the opposite side of the body part 15 from the member 18 is located and slidably arranged a space band member 22 having a centrally located dove-tailed tongue 23 extending from one side thereof and longitudinally beyond the same to any desired extent as best illustrated in Fig. 10. When the parts of the space band construction are arranged in assembled relation, as illustrated in Figs. 1 to 6 inclusive, the tongue

23 of the member 22 is fitted into the space 20 between the two tongues 19 of the member 18, whereby the tongues of the two movable space band members are interlocked, with each other as well as mounted 70 to slide freely upon the body 15 of the device, as well illustrated in Fig. 7.

When my improved space band construction is in use, with a matrix bar of the construction illustrated in Figs. 1 to 5, inclusive, 75 it is located entirely below the matrix members or matrix portion of the bar, but whether employed in connection with a matrix bar or to constitute an independent device, as illustrated in Fig. 6, there is a wedge-shaped stationary part 24 mounted on the upper part of the body of the band and on the same side thereof as the movable wedge-shaped part 18, the stationary member being so arranged that the point of the wedge shall 80 extend in the opposite direction from the corresponding extremity of the movable member 18. Furthermore, this stationary member, when the space band is adjusted for spacing words during the linotype casting 85 operation has its point immediately above the casting space 25 indicated by dotted lines in Figs. 3, 4 and 5. When the space band is utilized for word spacing purposes, in linotype composition, it may be so adjusted that only the body 15 of the band will 90 perform the spacing function. In this case, it may be assumed that the band is so arranged that the casting space 25 is between the points of the two wedges 18 and 24. In 95 this case, the spacing is measured by the thickness of the body 15 of the band (see Fig. 3 of the drawing.) Now, if it is desired to increase the space between the words, the 100 movable member 18 may be adjusted to enter the casting space and increase the word spacing to any extent desired, depending upon the movement of this member. As illustrated in Fig. 4, the member 18 is adjusted to increase the word spacing to the maximum degree available by the body part 15 105 and the wedge-shaped movable member. As soon as the member 18 is adjusted for word spacing purposes, its point begins to overlap the oppositely disposed stationary wedge-shaped part 24 whereby the outer surface of the member 18 is made parallel with the body part 15. This is the function performed by the stationary part 24. Now, if 110 it is desired to further increase the space between the words or to space them to the maximum degree permitted by my improved construction, the movable member 22 will be raised to the position illustrated in Fig. 5, whereby it co-operates with the body part 15 115 and the movable member 18 to space the words as stated.

The stationary wedge-shaped part 24 is composed of two separated members 26 which are secured to the body part 15 by 120

means of rivets 27 or in any other suitable manner.

The inner walls of the body of the space band on the opposite sides of the opening 5 16 above the casting line are straight to correspond with the adjacent portions of the inner walls of the member 24 (see Figs. 14 and 15) to allow the tongues 19 of the member 18 to move toward the right with said 10 last named member when taking the position shown in Fig. 5. During this operation the tongue 23 is carried laterally with the tongues 19 as best illustrated in Fig. 15. It should also be explained that the tongues 19 15 and 23 are composed of spring steel and are of small cross sectional area whereby it becomes practicable to adjust the parts as shown in Fig. 5. Attention is also called to the fact that the thickness of the parts of the 20 device as shown in the edge and cross sectional views, is greatly exaggerated for clearness of illustration.

Having thus described my invention, what I claim is:

25 1. A space band composed of a body part and two coöperating members slidably mounted and independently adjustable thereon.

2. A space band composed of a body part 30 of uniform thickness and two coöperating members movably mounted and independently adjustable thereon and arranged on opposite sides thereof.

3. A space band composed of a body part 35 and two coöperating members slidably mounted and independently adjustable thereon and arranged on opposite sides thereof, one of the said members being wedge shaped.

40 4. A space band composed of a body part and two distinct coöperating members independently adjustable thereon and arranged on opposite sides thereof, one of said members being wedge-shaped, the body part being provided with a wedge-shaped stationary part coöperating with the movable wedge-shaped member, substantially as described.

45 5. A space band composed of a body part, and two members movably mounted and independently adjustable thereon and arranged on opposite sides thereof, one member being wedge-shaped and the other member of uniform thickness.

6. A space band composed of a body part 55 and two members movably mounted and independently adjustable thereon and arranged on opposite sides thereof, one member being wedge-shaped and the other member of uniform thickness, the body part of 60 the band being equipped with a stationary wedge-shaped member arranged on the same side as the wedge-shaped movable member, the points of the movable and stationary wedge-shaped parts being directed toward 65 each other, whereby they are adapted to cooperate, substantially as described.

7. A space band composed of a body part and two distinct members independently adjustable thereon to slide longitudinally 70 thereof and arranged on opposite sides, one of said members being wedge-shaped, and both members being interlocked with the body part when the construction is assembled. 75

8. A space band composed of a body part and two distinct members independently adjustable thereon to slide longitudinally thereof and arranged on opposite sides, the said members and the body-part being in- 80 terlocked when assembled.

9. A space band composed of a body part and two members mounted thereon to slide longitudinally thereof said members being independently adjustable and arranged on 85 opposite sides, one member having a dove-tailed interlocking connection with the body part, and the two members being similarly interlocked with each other.

10. A space band composed of a body part 90 having an elongated opening provided with beveled walls on opposite sides of said opening, a movable member arranged on one side of the body part and having dove-tailed tongues, whose outer walls engage the 95 beveled walls of the body part, the tongues of the movable member being spaced, and a second member mounted on the opposite side of the body part and having a tongue fitting in the space between the two tongues of the 100 movable member on the opposite side, substantially as described.

In testimony whereof I affix my signature in presence of two witnesses.

GEORGE T. WILLIAMS.
